ENGINE STOP MECHANISM.

1,109,611.

Specification of Letters Patent.

Patented Sept. 1, 1914.

Application filed September 27, 1910. Serial No. 583,999.

To all whom it may concern:

Be it known that I, EDGAR H. BRISTOL, a citizen of the United States, and a resident of Naugatuck, in the county of New Haven 5 and State of Connecticut, have invented an Improvement in Engine Stop Mechanisms, of which the following description, in connection with the accompanying drawings, is a specification, like letters on the 10 drawings representing like parts.

This invention relates to engine stop mechanisms, and has for its object, among other things, to provide means whereby an engine may be stopped readily from different 15 stations if desired.

The character of this invention may be best understood by reference to the following description of an illustrative embodiment thereof shown in the accompanying 20 drawings, wherein—

Figure 1 is a side elevation of a portion of the stop mechanism embodying my invention; Fig. 2 is a front elevation thereof, partly in section; Fig. 3 is a detail plan 25 view of parts shown in Fig. 1; Fig. 4 is a horizontal section taken on line 4—4 of Fig. 1; and Figs. 5, 6 and 7 are detail views.

Referring to Figs. 1 and 2 of the drawings, an engine shaft 1 to which the fly wheel is 30 attached, loosely supports a valve eccentric 2, which is connected with the valve in the steam chest through a rod 3, secured to said eccentric by a two-part strap 4 connected by bolts 5. On one side of this valve eccentric 35 is a fixed collar 6 (see Figs. 2 and 4) having an integral lug 7 projecting from one face thereof into a semi-circular recess 8 (Fig. 5) in one face of said eccentric for a purpose hereinafter described. On the 40 opposite side of said eccentric is a drum 9 (Fig. 4) fixed to said shaft and having pins 10 axially movable therein, said pins being tapered at their inner ends so as to more readily enter holes 11 in the eccentric 2. 45 The shanks of the pins 10 are secured in any suitable manner to a cam faced disk 12 (Fig. 7) which is mounted to slide on said shaft. The drum 9 is reduced to receive a ring 14 having a cam face coöoperating with 50 the cam face of said disk 12 and is provided on its periphery with radially projecting stop lugs 15 hereinafter referred to. The contacting cam faces of the cam 12 and cam ring 14 are so shaped that when the parts

are in the position shown in Fig. 4, with 55 the pins 10 in engagement with the eccentric 2, and the engine running under normal conditions, the high parts of the cam 12 (see Fig. 2) are within the low parts of the cam ring 14, and vice versa. It will be apparent that if the cam ring 14 is turned relatively to said cam disk the latter together with the pins 10 will be moved outwardly thereby unclutching said pins from the eccentric 2 and releasing the latter. 60

Having described the eccentric and the means for connecting the same to the engine shaft, I will now describe the mechanism for controlling said connecting means.

Referring to Fig. 1, mounted on a fixed 70 part (not shown) adjacent to the eccentric 2 is a plate 16 having a coil 17 thereon, which is connected with a battery 18 through the wires 19. The circuit between said battery and coil is opened and closed by the push 75 buttons 20 that are located in convenient positions at points distant from the engine. Pivottally connected with said plate 16 is a trip lever 21 having a hook 22 thereon that engages the end of a lever 23 which is also 80 pivotally mounted on said plate and having a hook 24 at its outer end. A spring 25 connected with the plate and trip lever normally holds the hook 22 in engagement with said lever 23, as shown in Fig. 1. 85

In operation the rotation of the shaft 1 and drum 9 imparts movement to the eccentric 2 through the engagement of the pins 10 therewith. If it is desired to stop the engine from a remote point one of the buttons 20 is pressed, thus closing the electric circuit, and the current passing through the coil 17 actuates the trip lever 21 and releases the hook 22 thereof from the lever 23, which is now free and the forward end drops by 90 gravity into the path of the lugs 15 upon the cam ring 14. When one of the lugs is brought up against the hook 24 the cam ring 95 will come to a full stop and the continued rotation of the shaft 1 and eccentric 2 causes 100 the high parts upon the cam disk 12 to ride onto the high parts of the cam ring and said disk is thereby moved along the shaft 1, withdrawing the pins 10 from the eccentric against the resistance of the springs 26. The 105 connection between the eccentric 2 and shaft 1 is now broken or disorganized and the eccentric will hang loosely thereon, swinging

free until the lug 7 on the collar 6 (Figs. 2 and 5) engages the end of the recess 8. When freed from the shaft, the eccentric, by its movement, shifts the position of the valve in the steam chest, through the strap 3, so that the steam is admitted to the opposite end of the cylinder, reversing the engine. This action is such that the engine comes to a full stop, the piston cushioning against the steam so admitted and thereby assists in overcoming the inertia of the moving parts. By lifting the lever 23 so that the hook 24 thereof is disengaged from the lug 15 and engaging the hook 22 with said lever, the engine can be started again and the pins 10 will be moved into the eccentric 2 by the springs 26 when said pins are in registration with the holes 11 or the eccentric may be moved back by hand until the clutch pins 10 throw in. The lever is lifted out of the path of the lugs 15 automatically, when the shaft is rotated, by the contact of the lugs 27 on the cam 12 with the hook 24 of said lever.

25 It will be understood that my invention is not limited to the particular embodiment shown herein, but that various modifications may be made without departing from the spirit of my invention.

30 Claims:

1. An engine stop mechanism comprising in combination, a shaft, an eccentric loose thereon, means detachably connecting said eccentric to said shaft, and remotely operable means coöperating therewith for releasing said eccentric from said shaft.
2. An engine stop mechanism comprising in combination, a shaft, an eccentric loose thereon, means detachably connecting said eccentric to said shaft, and remotely operable electrical means coöperating therewith for releasing said eccentric from said shaft.
3. An engine stop mechanism comprising in combination, a shaft, a valve controlling 45 eccentric loosely mounted thereon, coöperating cam members fast and loose on said shaft respectively, and means operable by relative movement of said members for disconnecting one of them from said eccentric.

4. An engine stop mechanism comprising in combination, a shaft, a valve controlling eccentric loosely mounted thereon, coöperating cam members fast and loose on said shaft respectively, means operable by relative movement of said members for disconnecting one of them from said eccentric, and means for causing said relative movement of said members.

5. An engine stop mechanism comprising in combination, a shaft, a valve controlling eccentric loosely mounted thereon, coöperating cam members fast and loose on said shaft respectively, means operable by relative movement of said members for disconnecting one of them from said eccentric, and latch means for holding one of said members stationary to cause said relative movement.

6. An engine stop mechanism comprising in combination, a shaft, a valve controlling eccentric loosely mounted thereon, coöperating cam members fast and loose on said shaft respectively, means operable by relative movement of said members for disconnecting one of them from said eccentric, and electrically operated means for holding one of said members stationary to cause said relative movement.

7. An engine stop mechanism comprising in combination, a shaft, a valve controlling eccentric loose thereon, and means including a cam device for detachably connecting said eccentric to said shaft to permit said eccentric to turn with or independently of said shaft.

8. An engine stop mechanism comprising in combination, a shaft, an eccentric loose thereon, and means for connecting said eccentric to said shaft having provision for freeing the same from said shaft including manually controlled means and means operable by the engine.

In testimony whereof, I have signed my name to this specification, in the presence of two subscribing witnesses.

EDGAR H. BRISTOL.
